UNITED STATES PATENT OFFICE.

SAMUEL GEORGE TATE, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING MACHINES.

Application filed October 16, 1919. Serial No. 331,144.

To all whom it may concern:

Be it known that I, SAMUEL GEORGE TATE, a citizen of the United States, residing at Chicago, in the county of Cook, State of Illinois, have invented certain new and useful Improvements in Feeding Mechanisms for Sewing Machines, of which the following is a description, reference being had to the accompanying drawing, and to the figures of reference marked thereon.

The invention relates to new and useful improvements in feeding mechanisms for sewing machines, and more particularly to a feeding mechanism having main and auxiliary feed dogs which are given a differential movement relative to each other.

An object of the invention is to provide a differential feeding mechanism wherein an auxiliary feed dog is provided with a controlling mechanism including a shiftable fulcrum, the extent of movement of which may be varied for varying the feed stroke of the auxiliary feed dog.

A further object of the invention is to provide a feeding mechanism of the above character wherein the auxiliary feed dog is pivotally mounted on the feed bar which carries the main feed dog and receives all its movements from said feed bar.

A still further object of the invention is to provide a sewing machine having a relatively small work supporting arm with a main feed dog and an auxiliary feed dog disposed at the free end thereof and wherein said feed dogs are mounted on a single feed bar extending lengthwise of the arm and forming the sole driving connection for the feed dogs, and wherein a controlling mechanism is associated with the auxiliary feed dog for modifying the extent of movement imparted to the auxiliary feed dog by the feed bar.

These and other objects will in part be obvious and will in part be hereinafter more fully disclosed.

In the drawings, which show by way of illustration one embodiment of the invention:—

Figure 1 is a longitudinal sectional view through a work supporting arm having my improved feeding mechanism applied thereto;

Fig. 2 is a view, partly in plan and partly in horizontal section, of the same;

Fig. 3 is a sectional view taken on the line 55 3—3 of Fig. 1;

Fig. 4 is a sectional view taken on the line 4—4 of Fig. 1;

Fig. 5 is a perspective view of the main feed dog; 60

Fig. 6 is a side view of the auxiliary feed dog;

Fig. 7 is a plan view of the auxiliary feed dog;

Fig. 8 is a rear view of the auxiliary feed 65 dog;

Fig. 9 is a detail view showing in side elevation the feed bar, the feed dogs, and the operating devices therefor, said feed dogs being on their return stroke and showing 70 in dotted lines the dogs at the end of the rearward stroke;

Fig. 10 is a view similar to Fig. 9, but showing the feed dogs on their forward stroke and in dotted lines the extreme forward end of their stroke; 75

Fig. 11 is a diagrammatic view showing the movements of the main feed dog and the movements of the auxiliary feed dog and the arrangement of the parts which give to 80 the auxiliary feed dog a differential movement; and

Fig. 12 is a sectional view taken on the line x—x of Fig. 1.

The invention is directed broadly to a 85 feeding mechanism for sewing machines having a feed bar on which a main feed dog is rigidly mounted and on which an auxiliary feed dog is pivotally mounted so that it may be given a feed travel equal to or 90 greater than the feed travel of the main feed dog. The invention is particularly adapted to a machine of the type wherein the material being stitched is tubular in form and is supported by a suspended arm 95 and during the stitching operation is fed off from the end of the arm.

It is the purpose of this invention to provide a differential feeding mechanism which may be placed in a small compass so that 100 the arm in which it is placed may be made relatively small, and also to provide a feeding mechanism wherein the main feed dog and the auxiliary feed dog derive all of their movements from a single driving connection 105 which extends lengthwise of the arm. To this end, the main and the auxiliary feed dogs are mounted on the feed bar, as above

- noted, and both of these feed dogs are disposed at the free end of the feed bar. The feed bar is moved endwise and is raised and lowered. The movements imparted to the auxiliary feed dog by the feed bar are modified by controlling devices which are connected to the feed bar near the free end thereof.
- Referring more in detail to the drawings, which show one embodiment of the invention, the main feed dog is illustrated at 1^a and the auxiliary feed dog at 2^a. These feed dogs are carried in the forward end of a feed bar 3^a. The feed bar 3^a is pivotally connected at 4^a to a forked arm 5. The bar lies between the forked portions of the arm and a pivot bolt passes therethrough uniting this forked arm to the feed bar. This forked arm is mounted to swing upon an eccentric 6 which is fixed to a shaft 7. The shaft 7 is mounted in suitable bearings in the arm 8 of the machine and is provided with a suitable slot at one end thereof whereby it may be rotated. A set-screw 9 holds the shaft in an adjusted position. By rotating the shaft, the eccentric 6 will be shifted and thus the feed bar 3^a will be raised and lowered to bring it into proper cooperation with the fabric.
- The main feed dog is provided with fabric engaging teeth 10 and with a shank 11 which fits in a suitable recess in the feed bar 3^a and is secured therein by screws passing through slots 12. The auxiliary feed dog 2^a is provided with fabric engaging teeth 13, see Figs. 6 to 8, inclusive. Said auxiliary feed dog also has depending arms 14 and 15. These arms are formed with aligned openings adapted to receive a screw 16, see Fig. 1, which passes through the feed bar so that the auxiliary feed dog is supported by the feed bar but is pivotally supported thereby so that said auxiliary feed dog may swing upon the feed bar.
- The arm 15 of the auxiliary feed dog extends downwardly below the pivot and is formed with an opening 17. A link 18 is pivotally connected to the arm 15 by a screw 19 which is threaded into the opening 17.
- The screw becomes the fulcrum for the auxiliary feed dog and will hereinafter be referred to as the fulcrum 19 for said auxiliary feed dog. A segment arm 20 is mounted to rock on a shaft 21 which is fixed in suitable bearings in the work arm 8 by means of a set-screw 22, see Fig. 4. This segment arm is formed with a segmental slot 23. A link 24 is pivoted at 25 to the feed bar 3^a and is pivoted at 26 to the segment arm 20. A shoe 28 is mounted so as to slide freely in the slot 23. A bolt 29 passes through said shoe 28 and is held therein by a screw 30 which threads into the end thereof. Said bolt 29 has a threaded opening 33 formed therein. The shoe

28 has a reduced section 32 which receives the end of the link 18, the end of the link thus being held between the segment arm 20 and the head of the screw 30.

From the above, it will be apparent that I have provided a controlling mechanism for the auxiliary feed dog which serves to shift the fulcrum of the auxiliary feed dog, and it is this shifting of the fulcrum of the auxiliary feed dog that modifies the extent of movement imparted to the auxiliary feed dog by the feed bar. This controlling mechanism is all disposed adjacent the end of the work supporting arm and the movements imparted thereto for shifting the fulcrum are derived from the feed bar.

The extent of movement imparted to the shoe 28 may be varied by shifting the same in the segmental slot 23. I prefer to accomplish this by means of an adjusting screw 31 which engages a threaded opening 33 in the head of the bolt 29. The upper end of this threaded screw 31 is formed with a balled head 34 which has a suitable slot for receiving a screw-driver. The balled head 34 sets in a suitable ball socket in the upper face of the segment arm 20 and a cap plate 35 also having a ball socket and secured to the segment arm by screws 36 overlies the balled head on the screw 31 and keeps the same from endwise movement, although said balled head and socket connection permits the screw to shift and permit the shoe 28 to follow the segmental slot 23. By turning this screw 31, the point of connection between the link 18 and the segment arm 20 may be positively shifted and held in an adjusted position.

The feed bar 3^a is moved endwise by a lever 37 which is pivotally connected at 38 to a second lever 39. The lever 39 is fulcrumed at 40 to the work arm 8. The lever 39 has a fork 41 at its upper end cooperating with an eccentric 41^a on the operating shaft 42. The lever 37 cooperates with an eccentric 43 on this same operating shaft 42.

The operation of the feeding mechanism will be made more clear by reference to Figs. 9, 10 and 11. In Fig. 11, the fulcrum point for the segment arm 20 is indicated at *o*. The path of movement of the pivotal connection between the link 18 and the segment arm 20 is indicated at *a*—*a*. The path of movement of the pivotal connection between the link 24 and the segment arm 20 is indicated at *b*—*b*. The path of movement of the pivotal connection 25 between the link 24 and the feed bar is indicated at *c*. The path of movement of a point on the main feed dog is indicated at *g*; the path of movement of a point on the auxiliary feed dog is indicated at *f*; the path of movement of the pivotal point 16 connecting the auxiliary feed dog with the feed bar is indicated at *h*.

at *e*, and the path of movement of the fulcrum 19 of the auxiliary feed dog is indicated at *d*. Similar positions of these various points are indicated at 1, 2, 3 and 4 in this diagrammatic view.

When the feed dogs are in the full line position indicated in Fig. 9, they are at the extreme lower position or at the point 4. As the feed dogs move from this full line position to the dotted line position indicated in Fig. 9, the feed dogs move to the points 1 and likewise the other parts move to the points 1. It will be noted that the feed bar is moving rearwardly and also moving upwardly. The points moving along the paths *a*—*a* and *b*—*b* are moving downwardly, and as these points are at the right of the point *o*, the lower end of the auxiliary feed dog will move to the right and upwardly, as viewed in Fig. 11. The pivotal point for the auxiliary feed dog will also move to the right and upwardly by reason of the fact that the feed bar is moving to the right and upwardly. The extent of movement of the pivotal connection between the auxiliary feed dog and the feed bar to the right, however, is greater than the extent of movement of the fulcrum of the auxiliary feed dog, indicated at *d*, and this results in a greater movement to a point in the upper end of the auxiliary feed dog indicated by the path of movement *f* than is imparted to a point in the main feed dog, the path of movement of which is indicated at *g*. The feed bar then moves upwardly and forwardly to the full line position indicated in Fig. 10, and the points to which reference has been made above all move to the positions indicated at 2. The feed dogs are now in engagement with the material and are moving it forward.

It will be noted that the feeding movement of the upper end of the auxiliary feed dog is greater than the feeding movement of the main feed dog and, therefore, the material will be gathered and thereby prevent any stretching of the material which would otherwise occur when passing under the presser foot. This travel of the auxiliary dog is due to the fact that the movement of the fulcrum for the lower end of the auxiliary feed dog is less than the stroke of the main feed dog during this period. The fabric engaging surface of the auxiliary feed dog is curved about a point coincident with the pivotal connection of the auxiliary feed dog to the feed bar, and a line passing through the extreme upper points of the fabric engaging teeth of the main feed dog is substantially tangential to the curve of the teeth of the auxiliary feed dog.

From the above, it will be apparent that I have provided a feeding mechanism

which is composed of comparatively few parts and wherein the two feed dogs are both mounted at the free end of the feed bar. These feed dogs are moved up and down with the feed bar, and all fabric engaging movements of the feed dogs are derived from the endwise movement of a single feed bar extending lengthwise of the work supporting arm. It will also be apparent that the auxiliary feed dog is given a differential movement through the aid of controlling devices which shift the fulcrum of the auxiliary feed dog, and no actuating parts or driving connections extend along the tubular arm except the single feed bar.

By shifting the connection between the link 18 and the segment arm 20, the extent to which the fulcrum 19 of the auxiliary feed dog shifts is varied and thereby the differential movements given to the auxiliary feed dog is varied. The slot in the segment arm 20 is so shaped that, when this pivotal point of connection with the link 18 is at the extreme upper end of the slot, the fulcrum 19 moves to the same extent as the feed bar and the auxiliary feed dog moves substantially in unison with the main feed dog, and as said pivotal connection is moved downwardly along the segmental slot, the differential movement gradually increases.

It is obvious that minor changes in the details of construction and the arrangement of the parts may be made without departing from the spirit of the invention as set forth in the appended claims.

Having thus described the invention, what I claim as new and desire to secure by Letters-Patent is:—

1. A sewing machine including in combination, a cylindrical work supporting arm, a main feed dog located at the outer end of said work supporting arm, an auxiliary feed dog located at the outer end of said work supporting arm, a single driving connection extending along said work supporting arm for imparting feeding movements to both of said feed dogs, and means operated by said single driving connection for modifying the movements imparted to said auxiliary dog, whereby the extent of feeding movements imparted to the two feed dogs are different.

2. A sewing machine including in combination, a work supporting arm projecting away from the operator, a feeding mechanism for feeding the material being stitched off from the end of said arm including a main feed dog operating at the outer end of said work supporting arm, an auxiliary feed dog located adjacent the main feed dog and operating upon the material before it reaches the main feed dog, a single driving connection extending along said work supporting arm for imparting feeding

- movements to both of the feed dogs, means for raising and lowering the feed dogs, and means located adjacent the outer end of the work supporting arm for modifying the 5 feeding movements imparted to the auxiliary feed dog, whereby said feed dogs are given differential feeding movements.
3. A sewing machine including in combination, a work supporting arm projecting 10 away from the operator, a feeding mechanism for feeding the material being stitched off from the end of the arm including a feed bar extending lengthwise of the arm and having a main feed dog rigidly secured 15 thereto, an auxiliary feed dog located adjacent the main feed dog and operating upon the material before it reaches the main feed dog, said auxiliary feed dog being pivoted to the main feed bar, means for raising and 20 lowering the feed bar, and means operated by the main feed bar for modifying the movement imparted thereby to the auxiliary feed dog, whereby said feed dogs are given a differential movement.
- 25 4. A sewing machine including in combination, a work supporting arm, a feed bar extending lengthwise of said arm, means connected to the inner end of said feed bar for moving said feed bar back and forth, 30 means for raising and lowering the forward end of the feed bar, a main feed dog rigidly carried by said feed bar, an auxiliary feed dog pivotally mounted on said feed bar adjacent the main feed dog, and a controlling 35 means associated with the auxiliary feed dog for varying the amount of movement imparted to the auxiliary feed dog by said feed bar.
- 40 5. A sewing machine including in combination, a work supporting arm, a feed bar extending lengthwise of said arm, means connected to the inner end of said feed bar for moving said feed bar back and forth, means for raising and lowering the forward 45 end of the feed bar, a main feed dog rigidly carried by said feed bar, an auxiliary feed dog pivotally mounted on said feed bar adjacent the main feed dog, and a controlling 50 means associated with the auxiliary feed dog for varying the amount of movement imparted to the auxiliary feed dog by said feed bar, said controlling means including a shiftable fulcrum for said auxiliary feed dog, a swinging segmental arm, a link connecting said arm to the fulcrum for said auxiliary feed dog, and means whereby the 55 connection between the link and the segmental arm may be shifted for varying the extent of movement of the fulcrum for said auxiliary feed dog.
- 60 6. A sewing machine including in combination, a work supporting arm, a feed bar extending lengthwise of said arm, means connected to the inner end of said feed bar for moving said feed bar back and forth, 65

means for raising and lowering the forward end of the feed bar, a main feed dog rigidly carried by said feed bar, an auxiliary feed dog pivotally mounted on said feed bar adjacent the main feed dog, and a controlling 70 means associated with the auxiliary feed dog for varying the amount of movement imparted to the auxiliary feed dog by said feed bar, said controlling means including a shiftable fulcrum for said auxiliary feed dog, a swinging segmental arm, a link connecting said arm to the fulcrum for said auxiliary feed dog, and means whereby the connection between the link and the segmental arm may be shifted for varying 75 the extent of movement of the fulcrum for said auxiliary feed dog, said shiftable connection between the link and the segmental arm being constructed so that said fulcrum may be shifted in timing with the movements of the feed bar and the auxiliary feed dog moved in unison with the main feed dog.

7. A sewing machine including in combination, a work supporting arm, a feed bar 90 extending lengthwise of said arm, means connected to the inner end of said feed bar for moving said feed bar back and forth, means for raising and lowering the forward end of the feed bar, a main feed dog rigidly carried by said feed bar, an auxiliary feed dog pivotally mounted on said feed bar adjacent the main feed dog, and a controlling 95 means associated with the auxiliary feed dog for varying the amount of movement imparted to the auxiliary feed dog by said feed bar, said controlling means including a pivoted segmental arm, a link connected to said arm and to said feed bar whereby the feed bar oscillates said arm, said arm having a segmental slot therein, a block shiftable in said slot, and a link connecting said block to the lower end of said auxiliary feed dog.

8. A sewing machine including in combination, a work supporting arm, a feed bar extending lengthwise of said arm, means connected to the inner end of said feed bar for moving said feed bar back and forth, means for raising and lowering the forward 110 end of the feed bar, a main feed dog rigidly carried by said feed bar, an auxiliary feed dog pivotally mounted on said feed bar adjacent the main feed dog, and a controlling 115 means associated with the auxiliary feed dog for varying the amount of movement imparted to the auxiliary feed dog by said feed bar, said controlling means including a pivoted segmental arm, a link connected to said arm and to said feed bar whereby the feed bar oscillates said arm, said arm having a segmental slot therein, a block shiftable in said slot, and a link connecting said block to the lower end of said auxiliary feed dog, and an adjusting screw having a ball headed 120

socket connection with the segmental arm and a threaded connection with said block for shifting the block in said slot.

9. A sewing machine including in combination, a work supporting arm, a feed bar extending lengthwise of said arm, a main feed dog rigidly carried by said feed bar, means for giving said feed bar back and forth and up and down movements, an auxiliary feed dog pivotally mounted on said feed bar adjacent the main feed dog, and a controlling means associated with the auxiliary feed dog for varying the amount

of movement imparted to the auxiliary feed dog by said feed bar, said controlling means including a pivoted segmental arm, a link connected to said arm and to said feed bar, a block shiftable on the segmental arm, adjusting means carried by the arm for shifting the block on the arm and holding said block in adjusted positions, and a link connected to the block and to the lower end of the auxiliary feed dog.

In testimony whereof, I affix my signature.

SAMUEL GEORGE TATE.
